UNITED STATES PATENT OFFICE.

CHARLES G. BUJARSKY, OF ANDERSON, INDIANA.

DESIGN FOR A NOVELTY MITTEN.

59,182.

Specification for Design.

Patented Oct. 4, 1921.

Application filed July 30, 1920. Serial No. 400,247. Term of patent 14 years.

To all whom it may concern:

Be it known that I, CHARLES G. BUJARSKY, a citizen of the United States, residing at Anderson, in the county of Madison and State of Indiana, have invented a new, original, and ornamental Design for a Novelty Mitten, of which the following is a specification, reference being had to the accompanying drawing, forming part thereof.

The figure is a front plan view of my novelty mitten bearing my new design, the hand of the person holding the aforesaid covering or mitten bearing the design being shown in dotted lines within the mitten, the dotted line showing of a person's hand within the mitten not being a part of my design and expressly disclaimed.

I claim:

The ornamental design for a novelty mitten, as shown.

CHARLES G. BUJARSKY.
